ELECTRIC WAVE TRANSMITTING MEANS

Filed Aug. 16, 1922

Inventor:
William S. Gorton
by J. E. Roberts Atty.

UNITED STATES PATENT OFFICE.

WILLIAM S. GORTON, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRIC WAVE-TRANSMITTING MEANS.

Application filed August 18, 1922. Serial No. 582,112.

- This invention relates to electric wave transmitting apparatus, especially push-pull electron discharge amplifier circuits, and aims to provide apparatus and circuits which will avoid the use of transformers and efficiently transmit currents of low frequency, and will, in the case of the push-pull amplifier, obviate any necessity for insulating the amplifier batteries from ground.
- 10 The push-pull amplifier circuit, shown for instance in United States patent to Colpitts, No. 1,128,292, February 16, 1915, electric wave amplifier, has a transformer coupling in order to apply to the grids of two tubes voltages equal in amount but differing in phase by 180° . It is at times undesirable to use transformer coupling in amplifiers, especially where currents of very low or very high frequencies are to be amplified. With 20 an ordinary push-pull circuit, whenever one side of the line is grounded, if a non-inductive coupling such as a condenser-resistance or straight resistance coupling, instead of a transformer coupling, is used between the line and the amplifier, the cathodes of the tubes cannot be grounded as usual, since there would then be a short circuit from the ground at the cathodes to the ground on the line. Thus, with such a circuit there is no 25 alternative to grounding the grid of one of the tubes, which necessitates the obviously undesirable course of insulating various batteries, or their equivalent, from ground.
- In accordance with the invention a three 30 electrode electron discharge tube circuit, arranged to give zero amplification, is connected in circuit between the line and the input circuit of one of the amplifier tubes of a push-pull amplifying stage, for the purpose of shifting the phase of the line voltage 180° and thus providing the proper phase difference between the voltages applied to the grids of the two amplifying tubes. Thus, regardless of whether the line be grounded, 35 the entire line voltage can be applied to the grid of one of the amplifying tubes, a voltage of equal value and opposite phase being applied to the grid of the other amplifying tube, and the cathodes of all of the tubes 40 can be grounded. An especially useful application of this type of circuit is the case in which two non-inductively coupled stages of amplification are to be employed and the
- second stage is to be a push-pull stage to avoid distortion which would otherwise occur because of the large amount of power handled by the second stage. In this case it is, as usual, desirable that the cathode of the amplifying tube of the first stage be grounded, and this means, of course, that even if there is no ground on the line outside of the amplifier, one side of the circuit feeding the push-pull stage is grounded if the full line voltage is applied to the amplifying tube of the first stage through a non-inductive coupling, or in other words, if the first stage is non-inductively coupled to the line and is not a push-pull stage.
- The drawing shows one embodiment of the invention.
- As shown in the drawing, an incoming line 1 and an outgoing line 3 are non-inductively coupled through a two stage amplifier 5, the second stage of which comprises tubes 7 and 9 connected in push-pull relation, the first stage comprising an amplifying tube 11 and a phase reversing tube 13. The output voltage of tube 11 is applied across the grid and filament of tube 7 through the condenser-resistance coupling comprising condenser 15 and resistance 17. The output voltage of tube 11 is also applied across the input leads of a potentiometer 19 which has its output leads connected to the grid and filament of tube 13. A condenser 21 in the input lead of the potentiometer which is connected to the plate of tube 11 prevents flow of direct current from the "B" battery 23 of the amplifier 5 to the grid of tube 13. Plate current for tube 11 is supplied from battery 23 through an impedance 25 which is preferably a non-inductive resistance. Similarly, battery 23 supplies plate current for tube 13 through resistance 27.
- The output voltage of tube 13 is applied across the grid and filament of tube 9 through the condenser resistance coupling comprising a condenser 29 and a resistance 31. The output voltage of the second stage 35 of the amplifier, that is, the output voltage of the push-pull stage comprising tubes 7 and 9, is applied to line 3 through the condenser resistance coupling comprising condensers 33 and 35 and non-inductive resistance 37 and 39. Plate current for tube 7 is

supplied from battery 23 through resistance 37; and plate current for tube 9 is supplied from battery 23 through resistance 39.

The adjustment of potentiometer 19 is such that the voltage applied to the input circuit of the tube 9 is equal, though opposite in phase, to the voltage applied to the input circuit of the tube 7.

The cathodes of all of the tubes are preferably grounded, as shown, to reduce the capacity to ground of the connecting wires and thereby decrease the tendency of the repeater to sing.

Preferably, condensers 21 and 29 should each have twice the capacity of condenser 15, since condensers 21 and 29 are serially interposed between the plate of tube 11 and the grid of tube 9.

The impedances of condensers 15, 21 and 29 should be small compared with the impedances of resistances 17, 25, and 31 in order that the phase of the voltage delivered by tube 11 may be changed by 180 degrees with a high degree of accuracy. It is particularly advantageous to employ this phase shifting expedient in the voltage-amplifying stages of an amplifier, where the distortion introduced by the tubes is much less than it is in the power stages. Thus, in the drawing, the first amplifying stage, comprising tubes 11 and 13, may well be a voltage amplification stage, and the second stage, comprising tubes 7 and 9, may well be a power amplification stage.

The invention claimed is:

1. The combination with a push-pull amplifier comprising two amplifying elements having an input circuit including portions individual to said elements and a grounded portion symmetrically related to said elements, of an unsymmetrically grounded line, and non-inductive means for coupling said line to said individual portions of said input circuit.

2. A line, two three-electrode electron discharge tubes each having a grounded cathode, and a non-inductive coupling means for applying the undivided voltage of the line to the cathode and the control electrode of one of said tubes and for applying the undivided voltage of the line in reversed phase to the cathode and the control electrode of the other tube.

3. A system comprising two electron discharge amplifiers connected in push-pull relation, an electron discharge tube having an output circuit and a control circuit, means for supplying electromotive force waves to said control circuit and one of said amplifiers in parallel, and means connecting said output circuit to said other amplifier.

4. A system comprising an electric wave transmitting apparatus having a divided input circuit, a phase changing device, means for supplying electromotive force waves to

one division of said input circuit and said phase changing device in parallel, and means connecting said phase changing device to another division of said input circuit.

5. A system comprising an electric wave transmitting apparatus having a divided input circuit, an electron discharge tube having an output circuit and a control circuit, means for supplying electromotive force waves to said control circuit and one division of said input circuit in parallel, and means connecting said output circuit to another division of said input circuit.

6. An amplifier circuit comprising a first stage and a second stage, said second stage comprising two electron discharge tubes connected in push-pull relation and said first stage comprising an electron discharge amplifying tube, said circuit also comprising a phase reversing three-electrode electron discharge tube, means connecting the output circuit of said amplifying tube to the input circuit of one of said push-pull tubes and the input circuit of said phase reversing tube in parallel, and means connecting the output circuit of said phase reversing tube to the input circuit of said other push-pull tube.

7. A line, three three-electrode electron discharge amplifying tubes, each having a grounded cathode, a non-inductive coupling means for applying the voltage of the line to one of said tubes, and a non-inductive coupling means for applying the output voltage of said one tube to the cathode and control electrode of another of said tubes and for applying said output voltage in reversed phase to the cathode and control electrode of the remaining tube.

8. In combination, a line having one side grounded, a pair of three-element space discharge devices connected in push-pull relation and having their cathodes both connected to ground, input terminals for said devices, and a non-inductive coupling connecting said line to the input terminals of said devices, said coupling including non-inductive means for producing a 180° difference in phase in the line voltages applied to the input terminals of the respective space discharge devices, whereby said devices are adapted to amplify electrical variations received over said line.

9. A line, two three-electrode electron tubes each having a grounded cathode, and a non-inductive coupling means for transferring voltage between two electrodes of one of said tubes and said line without substantial phase change, and for transferring voltage between the corresponding two electrodes of the other tube and the line with phase reversal.

10. A system comprising two electronic amplifiers connected in push-pull relation,

an electron tube having an output circuit and a control circuit, means connecting one of said circuits and one of said amplifiers, in parallel, to a line, and means connecting the other of said circuits and the other of said amplifiers.

11. A system comprising an electric wave transmitting apparatus having a divided circuit, a phase changing device, means for connecting one division of said circuit and 10 said phase changing device, in parallel, to a line, and means connecting the other of said divisions and said phase changing device.

In witness whereof, I hereunto subscribe 15 my name this 8th day of August, A. D., 1922.

WILLIAM S. GORTON.
